COMPOSITION FOR INHIBITING FOAM

Henry E. Tremain and Leslie R. Bacon, Wyandotte, Mich., assignors to Wyandotte Chemicals Corporation, Wyandotte, Mich., a corporation of Michigan

No Drawing. Application July 26, 1945,
Serial No. 607,276

2 Claims. (Cl. 252—321)

1
The present invention relates to a composition and a process for suppressing or inhibiting the formation of foam in aqueous systems or media, whether true solutions or colloidal suspensions, such as encountered in industrial processes, for example, industrial alkaline cleaning operations, distillation, paper making, textile treating and finishing, glue manufacture, sugar boiling and soap manufacture. The prevention of foaming difficulties in commercial bottle washing machines employing alkaline washing solutions constitutes a field of application to which our invention is particularly adapted.

In our co-pending application Serial No. 520,960, filed February 3, 1944, now U. S. Patent No. 2,407,589, we have disclosed a foam inhibitor and a process for suppressing the formation of foam in which the major active ingredient is tertiary amyl phenoxyethanol or p-tertiary amyl phenoxyethanol. These two compounds have displayed unusual foam inhibiting properties, not only with respect to their ability to "knock down" foam which has already been formed in industrial chemical process aqueous systems, but also with respect to their ability to maintain foam suppression for relatively long periods of time. As compared to foam inhibiting compositions heretofore known and used, the above mentioned compounds of our aforesaid co-pending application, when tested both in the field and in the laboratory under similar rigorous conditions, have displayed vastly superior foam inhibiting properties. We have now discovered that not only the two amyl phenoxyethanols above mentioned, but also organic chemical compounds corresponding to the following general formula, have similar outstanding anti-foaming properties:

$(R')_x = Ar-O-R-OH$

R, R' = alkyl radicals

Ar = aromatic hydrocarbon of the benzene series
 $x = 1$ or greater whole number

Exemplary of compounds coming within this general chemical formula are: di-tertiary amyl phenoxyethanol, p-tertiary amyl phenoxyethanol, di-tertiary amyl phenoxy propanol and di-tertiary amyl phenoxy isopropanol.

These phenoxy alkanols, when added to an aqueous body, have the tendency to remain in an undispersed condition, having the appearance of "floating lenses" on the surface of the aqueous body, particularly if the latter is relatively quiescent and not subject to agitation or stirring. It is, therefore, one of the prime objectives of our present invention to discover a spreading or dispersing agent capable of being admixed with these phenoxy alkanols and causing them to spread over and become dispersed in the aqueous body wherein the foam inhibiting action is desired. Although there are available a large num-

ber of hydrophile chemical compounds which are compatible with the phenoxy alkanol inhibitors of our invention, we have found that the following two chemicals best produce the spreading or dispersing action desired, namely: lecithin and "sodium petroleum sulfonates," namely: high molecular weight sodium salts of oil soluble sulfonic acids of alkyl aryl petroleum hydrocarbons, having from 20 to 30 carbon atoms. Where the term "sodium petroleum sulfonate" is hereinafter used in the specification and claims, it will mean the material as just defined. These sodium petroleum sulfonates are commercially available under the trade names "Petronate," "Oronite" and "Acto."

The presence of either one of these two dispersing agents in the amount of .05 to 5% by weight on the basis of the phenoxy alkanol compound, represents a suitable range of formulation. They are excellent dispersing agents where some degree of agitation or stirring is present in the aqueous system or medium since it induces an incipient spreading or dispersing action which is then augmented by the mechanical agitation.

Under most conditions of use, only a very small amount of the foam inhibiting compositions of our invention need be employed, viz: a minimum of 0.001% by weight (on basis of active foam inhibiting ingredient present) of the aqueous body or solution to which the inhibitor compositions are added.

A further objective of the present invention has been to discover relatively chemically but physically effective inert vehicles or carriers for these phenoxy alkanol compositions whereby they may be compounded in a convenient and suitable form for handling, packaging, and use. We have found that such vehicles or carriers selected from the group consisting of aliphatic 3 to 6 carbon atom-containing ketones, alcohols and glycolic ethers, make excellent liquid carriers which are compatible with the aforesaid amyl phenoxy alkanols both chemically and physically.

The preferred liquid vehicles which are both chemically and physically compatible with the amyl phenoxy alkanols, and are found within the group consisting of aliphatic 3 to 6 carbon atom-containing ketones, alcohols and glycolic ethers are: tertiary butanol, iso-propanol, methyl isobutyl ketone, n-butanol, sec-butanol, the amyl alcohols, di-ethylene glycol monomethyl ether (available under the trade-name "Methyl Carbitol"), diethylene glycol monoethyl ether (available under the trade-name "Ethyl Carbitol"), acetonylacetone (2, 5 di-ketohexane), and 2-methyl-2, 4-pentanediol.

From the foregoing list of suitable liquid diluents, 2-methyl-2, 4-pentanediol is the one most suitable and preferred for our composition. When 2-methyl-2, 4-pentanediol is present in conjunc-

tion with the sodium petroleum sulfonate, a remarkably enhanced dispersing action takes place. In fact, in the presence of the last two mentioned compounds, the amyl phenoxy alkanol becomes so rapidly and thoroughly dispersed in the aqueous body that no mechanical agitation is required to complete or maintain dispersion.

We have devised a method of testing foam inhibiting properties, reproducing as closely as possible, the severest conditions of commercial foam inhibiting problems. This test procedure is performed in an apparatus which we have chosen to call a "dynamic foaming machine" and is described in detail in our aforesaid co-pending application Serial No. 520,960.

Several exemplary foam inhibiting compositions made according to the principle of our invention have been subjected to this test procedure, and the results thereof are set forth in the following table:

nute amounts of dye may be added if a distinctive color is desired.

The presence of the water in the formulations of Examples 4, 5 and 6 reduces the viscosity of the mixture and aids in its subsequent use and introduction into aqueous baths or solutions. These latter formulations, consisting of the four ingredients, i. e.: the phenoxy alkanol foam inhibitor, the aliphatic alcohol blending agent, the sodium petroleum sulfonate dispersing agent, and water are in single phase physical form, viz: they do not form, or separate out into, two or more layers or heterogeneous physical phases. This extraordinary physical property (when it is considered that certain of the ingredients are otherwise individually physically immiscible or incompatible) is most beneficial. The single phase mixture need not be agitated or shaken up each time it is to be used. Also the uniformity of 15 the formulation for each time a fractional quan- 20

Table

Foam Inhibitor	Amount of Formulation in Dynamic Test Sol'n.	Percentage of Amyl Phenoxy Alkanol Present	Time to Suppress Foam	Duration of Foam Suppression
EXAMPLE 1				
Di-tertiary amylphenoxyethanol, 100% ¹	Grams 10	0.1	Minutes 2	Hours 17
EXAMPLE 2				
Di-tertiary amylphenoxyethanol, 94.8% Lecithin, 2% Tetradecanol, 5.0%	10	0.094	2½	15½
EXAMPLE 3				
Di-tertiary amylphenoxypropyl, 100% ¹	10	0.1	3½	5
EXAMPLE 4				
Di-tertiary amylphenoxyethanol, 30% 2-methyl-2, 4-pentanediol, 40% "Petronate H," 10% Water, 20%	33	0.1	1½	9½
EXAMPLE 5				
Di-tertiary amylphenoxyethanol, 30% 2-methyl-2, 4-pentanediol, 40% "Oronite Wetting Agent," 5% Water, 25%	33	0.1	1½	10
EXAMPLE 6				
Di-tertiary amylphenoxyethanol, 30% 2-methyl-2, 4-pentanediol, 35% "Acto 60," 10% Water, 25%	33	0.1	1½	9½

¹ All percentages given herein are by weight unless otherwise specified.

It will be noted in the composition of Example 2, that there is a small percentage of tetradecanol present. Other organic compounds, such as the several alcohols and esters (as noted in our said co-pending application Serial No. 520,960 as previously utilized anti-foaming agents) may be added in small amounts without going beyond the scope and spirit of our invention, since they do not detract from the foam inhibiting properties of the active amyl phenoxy alkanol ingredient, but do serve as a convenient formulating ingredient. By the same token, mi-

65 tity is withdrawn for use from a larger quantity in a container, is insured.

The foam inhibitor formulation of Example 4 of the foregoing table represents our preferred composition in the liquid form. In actual field tests, we have found that this formulation has displayed over two times the foam inhibiting properties of the same amount of di-tertiary amylphenoxyethanol alone. We have determined that the percentages of the respective ingredients therein may be varied over the following ranges, without sacrificing the water solution

dispersing abilities thereof: di-tertiary amyl phenoxyethanol 20 to 40%, 2-methyl-2, 4-pentanediol 35 to 50%, water 10 to 40% and sodium petroleum sulfonate 4 to 10%. Di-tertiary amyl phenoxy propanol may be substituted for the corresponding ethanol compound and with similar foam suppressing results.

The amounts of the anti-foaming agent which may be required vary widely according to the nature of the foam to be suppressed and the mechanical conditions which obtain, but in any case are very small, viz. as low as 0.001% by weight (on the basis of the active foam inhibiting ingredient present) of the aqueous body or system to which the inhibitor compositions are added. This is often sufficient and generally constitutes a suitable initial or trial addition.

Other modes of applying the principle of our invention may be employed, changes being made as regards to the details described, provided the features stated in any of the following claims or the equivalent of such be employed.

We, therefore, particularly point out and distinctly claim as our invention:

1. A composition for suppressing the formation of foam in aqueous systems consisting of, by weight, 20 to 40% di-tertiary amyl phenoxyethanol, 35 to 50% 2-methyl-2, 4-pentanediol, 10 to 40% water and 4 to 10% of a sodium petroleum sulfonate.

2. A composition for suppressing the formation of foam in aqueous systems consisting of, by weight, 20 to 40% of a compound selected from the group consisting of di-tertiary amyl phenoxyethanol and di-tertiary amyl phenoxypropanol, 35 to 50% 2-methyl-2, 4-pentanediol, 10 to 40% water and 4 to 10% of a sodium petroleum sulfonate.
